UNITED STATES PATENT OFFICE.

FRANK W. COLLINS, OF CORTLAND, NEW YORK.

VEHICLE-ROBE.

1,211,290.

Specification of Letters Patent.

Patented Jan. 2, 1917.

Application filed January 8, 1916. Serial No. 71,055.

To all whom it may concern:

Be it known that I, FRANK W. COLLINS, a citizen of the United States, and a resident of Cortland, in the county of Cortland and State of New York, have invented a certain new and useful Vehicle-Robe, of which the following is a specification.

This invention has for its object the production of a vehicle robe which can be readily adjusted and removed and which is particularly simple in construction, and highly efficient and comfortable in use; and the invention consists in the combinations and constructions hereinafter set forth and 15 claimed.

In describing this invention, reference is had to the accompanying drawings in which like characters designate corresponding parts in all the views.

20 Figures 1 and 2 are, respectively, front and rear elevations of a robe constructed in accordance with my invention, the head piece being shown as projecting upwardly in Fig. 1 and as folded down in Fig. 2. Fig. 25 3 is a sectional view on line A—A, Fig. 1. Figs. 4 and 5 are respectively, a front elevation and a plan view of the head piece showing its position when the head piece is buttoned around the head of the user. Figs. 6, 30 7 and 8 are respectively plan views of the detached front body piece and the right and left side flaps. Fig. 9 is a plan view of the blank of the head piece. Fig. 10 is a plan view of the blank of the muff. Figs. 11 and 35 12 are plan views of the parts of the boot.

This vehicle robe comprises, generally, a front body piece which extends from the feet to the neck of the user, a boot at the lower end of the body piece normally projecting forwardly therefrom and having its entrance opening facing rearwardly, and side flaps foldable rearwardly around the user's body, these side flaps extending the full length of the body piece and being normally arranged to stand at an angle to the body piece, and foldable into position to close the entrance opening of the boot. Preferably these side flaps are provided with arm holes at their upper ends.

40 50 1 designates the body piece, and 2 the boot. 3 are the side flaps.

The body piece is formed with a cutout 4, extending upwardly from its lower edge and the boot 2 includes triangular side walls 5 secured at one end to the body, and a wall connected to the upper and lower edges of

the side walls 5 forming the top wall 6 and bottom wall 7 of the boot. The opening 4 constitutes the entrance opening for the boot and the lower portion of this entrance opening is closed by a wall 8 which has extensions 9 at its ends secured to the rear face of the body 1. Preferably the top wall 6, the bottom 7 and the wall 8 are formed from a blank 10, and owing to the arrangement of 60 the side walls 5, top wall 6, and bottom 7, the boot is caused to project forwardly from the body 1 so that the feet of the user can be readily inserted therein.

The body piece 1 is formed with its side 70 edges angular, that is, the side edges converge downwardly at 11 from points 12 near and slightly above the waistline of the body piece 1, the side edges also converging upwardly at 13 from the points 12 toward the top or collar portion of the body piece 1.

The side flaps 3 are formed with the straight edges 14 contiguous to the body 1, and these straight edges 14 are secured to the inclined edges 11 and 13 of the body 80 piece so that the flaps are caused to normally stand at an angle to the body piece 1, and hence to have the tendency to remain in such a position that the user can readily work the side pieces around him and so that they will 85 remain easily in place after his feet have been inserted in the boot 2. These side flaps 3 preferably extend the full length of the body 1 and are provided with arm holes 15 near their upper ends.

90 As the lower ends of the side flaps extend to the lower edge of the body piece 1, the lower ends of the side flaps close the entrance opening 4 of the boot and lap the wall 8 which closes the lower portion of this opening 4, so that the feet of the user are snugly inclosed. The body piece is also provided with a suitable muff which consists of a piece 16 secured to the inner or outer face of the body piece 1, and is also provided 95 with slits by means of which the user's hands can be thrust into the muff from the outside of the body when the piece 16 is secured to the inner surface of body piece 1.

100 17 designates the head piece which is cut from the blank illustrated in Fig. 9, this head piece including a collar band 18 and flaps 19 arranged to come on opposite sides of the head as shown in Figs. 4, 5 when the head piece is buttoned around the head of 110 the wearer. These flaps normally stand in the same plane as the collar 18 when the

head piece is flat. By this construction, the head piece can be cut from a single piece of material. The head piece may be permanently or detachably secured to the body 5 and may be foldable out of and into the position shown in Fig. 2 or may be detachable.

This vehicle robe is particularly advantageous in that it is comparatively simple in construction, and is especially advantageous 10 in that it can be readily adjusted and removed by the user himself without outside aid.

What I claim is:

1. A vehicle robe comprising a front body 15 piece having its side edges thereof converging from near the waistline to the collar line thereof, and side flaps extending substantially the full length of the body piece and having straight edges contiguous to the 20 body piece, the straight edges being secured to the angular edges of the body piece whereby the side flaps normally stand at an angle to the body piece, substantially as and for the purpose described.

2. A vehicle robe comprising a front body 25 piece having its side edges converging downwardly from points near the waistline toward the lower end thereof and converging upwardly from said points near the waistline to the collar line, side flaps oblong in general outline and having straight edges which are secured to the angular side edges of the body piece whereby the side flaps normally stand at an angle to the body piece 30 and in position to be readily wrapped around the user's body, substantially as and for the purpose specified.

3. A vehicle robe comprising a front body 40 piece having side edges thereof converging from near the waistline to the collar line thereof, and side flaps foldable rearwardly and under the wearer, the side flaps extending substantially the full length of the body piece and having straight edges contiguous 45 to the body piece, the straight edges being secured to the angular edges of the body piece whereby the side flaps normally stand at an angle to the body piece, the side flaps having arm holes near their upper ends, substantially as and for the purpose set forth.

4. A vehicle robe comprising a body piece, side flaps on opposite sides of the body, and a forwardly extending boot at the lower end of the body piece and arranged to stand at 50 an angle to the body piece and having an entrance opening on the rear side thereof,

the boot also having a wall closing the lower portion of its entrance opening leaving the upper portion thereof open, the side flaps being foldable in position to close said entrance opening, substantially as and for the 55 purpose set forth.

5. A vehicle robe comprising a body piece and a forwardly projecting boot at the lower end, the boot including side walls standing at an angle to the body piece, a top wall inclining downwardly and forwardly from the front of the body piece and a bottom wall, the side walls of the boot holding the same in an angular relation to the body so that the wearer's feet can be readily inserted 65 therein, and a wall inclosing the lower portion of the entrance opening of the boot, and side flaps secured to the edges of the body piece and foldable rearwardly around the wearer and over the entrance opening of the 70 boot and lapping the wall across the lower portion of the entrance opening, substantially as and for the purpose specified.

6. A vehicle robe comprising a body piece, a forwardly projecting boot at the lower 75 end of the body piece including side walls standing at an angle to the body, a top wall inclining downwardly and forwardly from the front of the body and a bottom wall, the side walls of boot holding the same in an 80 angular relation to the body piece so that the wearer's feet can be readily inserted therein, a wall closing the lower portion of the entrance opening of the boot, and side flaps secured to the edges of the body piece 85 and foldable rearwardly around the wearer and over the entrance opening of the boot the side flaps lapping the wall across the lower portion of the entrance opening, said side flaps extending the full length of the 90 body piece and having arm holes at their upper ends, substantially as and for the purpose set forth.

7. A vehicle robe comprising a body piece, and a head piece comprising a neck band 100 and side pieces rising from the neck band and arranged in the same plane as the neck band and to come on the sides of the wearer's head when the side pieces are buttoned back of the user's head, substantially as and for 105 the purpose described.

In testimony whereof I have hereunto signed my name at Cortland, in the county of Cortland, and State of New York, this 18th day of December, 1915.

FRANK W. COLLINS.
